UNITED STATES PATENT OFFICE

164,282

TOP BURNER FOR A GAS RANGE

John E. Chambers, Shelbyville, Ind., assignor to
Chambers Corporation, a corporation of Indiana

Application January 14, 1950, Serial No. 7,253

Term of patent 14 years

(Cl. D81—10)

To all whom it may concern:

Be it known that I, John E. Chambers, a citizen of the United States, residing at Shelbyville, in the county of Shelby and State of Indiana, have invented a new, original, and ornamental Design for Top Burner for a Gas Range, of which the following is a specification, reference being had to the accompanying drawing, forming part thereof.

Fig. 1 is a top plan view of the top burner for a gas range showing my new design;

Fig. 2 is a side elevation thereof;

Fig. 3 is an end elevation thereof; and

Fig. 4 is a bottom plan view thereof.

The dominant features of my design reside in the portions shown in full lines.

I claim:

The ornamental design for a top burner for a gas range, as shown and described.

JOHN E. CHAMBERS.
